UNITED STATES PATENT OFFICE

CLARENCE A. BRUNING, OF COLFAX, WASHINGTON

DESIGN FOR A FLORAL RACK OR SIMILAR ARTICLE

Application filed February 28, 1931. Serial No. 38,863. Term of patent 3½ years.

To all whom it may concern:

Be it known that I, CLARENCE A. BRUNING, a citizen of the United States of America, residing at Colfax, in the county of Whitman and State of Washington, have invented a new, original, and ornamental Design for a Floral Rack or Similar Article, reference being had to the accompanying drawing, forming a part thereof.

The figure is a perspective view of a floral rack or similar article, showing my new design.

I claim:

The ornamental design for a floral rack or similar article, substantially as shown.

CLARENCE A. BRUNING.
